FRAME

William D. Antrim, Gloucester, N. J., assignor to
 Roberts & Mander Stove Company, Philadelphia, Pa., a corporation of Pennsylvania

Application October 15, 1934, Serial No. 748,392

4 Claims. (Cl. 189—34)

This invention relates to new and useful improvements in metal frame structures and the method of making the same, and relates more particularly to novel base frame structures for use in conjunction with cooking ranges, cabinets and other like structures.

The principal object of the invention is to provide a novel metal frame structure of the character set forth having an integral base flange 10 projecting outward horizontally from the frame throughout its extent.

Another object of the invention is to provide a metal frame structure of the stated character constructed from angle bar stock wherein one leg 15 of the angle bar constitutes a horizontally projecting base flange constructed and arranged so that the peripheral radius of said flange at a curvature or corner in the frame is equal to the width of the said flange at any other point in said frame.

Another object of the present invention is to provide a frame structure of the stated character which is particularly adaptable to present day cabinet ranges and the like.

Another object of the invention is to provide a frame structure of the character set forth which is novelly constructed and arranged to provide a relatively large base surface area.

Another object of the invention is to provide a 30 base frame of the character stated for cabinet ranges which is so constructed as to greatly reduce the possibility of damage to the cabinet and chipping of enamel from the wall panels thereof during shipment.

A further object of the invention is to provide a frame structure of the character set forth which may be entirely fabricated from start to finish without subjecting the metal to a heat.

Certain other objects of the invention and the 40 features and details of construction thereof are set forth hereinafter and shown in the accompanying drawings, in which:

Fig. 1 is a view in perspective of an angle bar from which a frame is made in accordance with the present invention.

Fig. 2 is a view in perspective similar to the disclosure in Fig. 1 showing a number of apertures formed in the angle bar at predetermined spaced intervals.

Fig. 3 is an enlarged view in plan of a portion of an apertured angle bar mounted in a bending or corner forming device.

Fig. 4 is a view in section on line 4, 4, Fig. 3.

Fig. 5 is a view in plan similar to the disclosure

in Fig. 3 after the bar has been bent to form a corner of the frame.

Fig. 6 is a view in plan showing a completed rectangular base frame for a cabinet range made in accordance with the present invention.

Fig. 7 is an enlarged view in perspective showing a corner section of the frame disclosed in Fig. 6.

Fig. 8 is an enlarged view in section through the base frame structure showing a wall panel of a 10 cabinet range mounted thereon.

Fig. 9 is an enlarged view in plan of a corner of a base frame showing wall panels of a cabinet range associated therewith; and

Fig. 10 is a view similar to Fig. 9 showing another arrangement by which wall panels of a cabinet may be mounted with respect to the frame which forms the subject matter of the present invention.

Referring now more particularly to the drawings, a frame constituting the present invention is made from metal angle bar stock comprising the customary respectively perpendicular legs 1 and 2. As shown in the drawings, the leg 1 of the angle bar is of less width than the leg 2 thereof but this particular relationship is not essential and may be otherwise.

In making a frame in accordance with this invention a predetermined length of metal angle bar A, equal to the developed length of the proposed frame structure, is cut from the bar stock, and a predetermined number of apertures or openings 3 are punched or otherwise formed in the said angle bar at predetermined spaced intervals therealong, each particular aperture 3 being located along the angle bar A so that the transverse axis of said aperture will reside in the same plane as the axis about which the bar A will be bent to form a corner of the frame. The apertures 3 may be formed in the bar by an independent operation but for production work it is desirable to form the apertures in the bar at the same time that the desired predetermined length of the angle bar A is cut from the stock.

It will be noticed by a reference to Fig. 2 of the drawings that the apertures 3 formed at spaced intervals in the angle bar, are in each instance so positioned that metal is removed from both of the legs 1 and 2 of said bar, and that the greater portion thereof is removed from the first mentioned or shorter leg 1 than from the leg 2. The purpose for this particular arrangement of the apertures 3 in the angle bar with respect to the legs 1 and 2 thereof will be described more in detail hereinafter.

When the angle bar A has been cut to the desired length from the stock and the apertures or openings 3 have been formed therein as previously set forth, the said angle bar is placed in a bending device designated generally as 4.

Referring to Figs. 3, 4 and 5 of the drawings the bending device 4 comprises sections B and C pivotally connected at 5, each of said sections B and C including a bracket portion 6 and a projecting web 7 having a lip 8 for respectively embracing the legs 2 and 1 of the bar A. The sections of the clamp or bending device 4 are firmly secured to the leg 2 of the angle bar by means of bolts 9 threaded in the bracket portions 6 which embrace leg 2. As shown in the drawings one of the clamp sections C is provided with a handle 10 for actuating the same relatively with respect to the other section B about their common pivot 5. It should be noticed that the portions 6 of each section of the clamp grip the leg 2 of the bar A and support the same closely adjacent each end of the opening 3 in the bar, the purpose for which will be described hereinafter. With the clamp or bending device 4 firmly 25 in position on the angle bar A, one or both of the sections B and C thereof may be pivoted toward each other until the adjacent portions of the leg 2 of the bar are respectively at an angle of 90°, or any other particular angle that may be desired, thus forming a corner of the frame. The clamp or bending device 4 may then be removed from the bar by loosening the retaining bolts or screws 9.

With regard to the bending of the angle bar A to form a corner in a frame, it is pointed out that the principal object of the invention is to provide such a corner wherein the radius of the projecting horizontal leg 1 at said corner will be substantially equal to the width of the said leg at all other points throughout the frame; in other words, will be of substantially uniform constant width throughout the frame irrespective of any bending of the angle bar to form a corner therein. Obviously in order that the horizontal projecting base leg 1 may be of substantially uniform width throughout the entire frame, the periphery of said leg at the corner must have a curvature the peripheral radius of which is no greater than the width of the leg 1, and in order 40 to form such a curve with the leg 1 it is necessary that the metallic particles composing the same be stretched or elongated through circular arcs having a common center, the outermost or peripheral arc having a radius substantially equal 45 to the width of the leg.

In the present instance the stretching or elongation of the metallic particles in the horizontal leg 1 at a corner is made possible by the formation of the apertures 3 in the bar A, and it will be noticed that said apertures function to sever the leg 1 from the leg 2 between the ends of each opening 3 formed therein. Consequently with the portions 6 of the bending device 4 gripping the leg 2 adjacent each end of such an opening 3, actuation of the sections B and C of the device toward each other about their common pivot 5 will cause the metal in the horizontal leg 1 to be stretched or elongated in the manner previously described, and when so stretched or elongated the periphery of the leg 1 at the corner will form a curve the radius of which is substantially equal to the width of the said leg throughout the remainder of the angle bar A.

Furthermore it will be obvious that if the metal fibres in leg 1 are stretched or elongated at a

corner in the above manner, the metal fibres in the leg 2 must be compressed proportionately or a substantially equivalent amount of the metal must be displaced therefrom. Thus it will be seen that by severing the leg 2 from the leg 1 for the length of an opening 3, that portion of the leg 2 between the ends of said aperture being freed from connection with the horizontal leg 1, will be displaced outwardly with respect to the adjacent portions of the leg 2 and assume the form of a loop as shown in Fig. 4 of the drawings.

A particular feature of the invention resides in the fact that all of the operations herein described for making a frame in accordance with the present invention may be done cold without any heating of the metal whatever, and when all of the corners in a particular base frame structure have been formed in the manner described above, as for instance the rectangular base frame structure disclosed in Fig. 4, the adjacent ends of the angle bar may be welded or otherwise permanently secured together as indicated at 10.

It is desirable to point out at this time that in ordinary practice the corner angles of a frame made in accordance with this invention should be formed in machine operated mechanisms as contrasted to the manually operated clamp or bending device 4 which has been described herein solely for the purpose of showing in as simple a manner as possible just how the respectively perpendicular leg portions of the angle bar A are gripped or engaged by portions of any mechanism used so that the angle bar may be formed into a frame in accordance with the invention.

A frame structure made in accordance with this invention is of an extremely rigid nature and sufficiently durable to withstand many years of use. Such a frame is particularly adaptable for use as a base frame structure for modern ranges and other cabinet like structures of the more so-called modernistic design, wherein the wall panels extend continuously from the top to the bottom of such a structure, and may or may not be provided with supporting legs or castors.

For instance by providing such a base frame with a horizontal projecting base flange or leg 1, as shown in Fig. 8, a wall panel 11 stamped from metal sheet and provided with a peripheral flange 12 of a width substantially equal to the width of the upper surface of the said leg 1 may conveniently be mounted upon said base flange or leg 1 and secured thereto at its peripheral flange in any suitable manner. A reference to Fig. 8 will disclose that the particular arrangement just described will give a neat, clean-cut, external appearance to such a structure which is of pleasing appearance and in conformity with present day trends in the construction of household furniture such as cabinets, cabinet ranges and the like.

A solid wall panel of wood or other fibrous texture or composition (not shown) might readily be substituted for the stamped metal wall panel 11, with exactly the same result as far as the neatness and appearance of the structure are concerned, and in some structures, it may be desirable to provide the frame with a horizontal projecting flange 1 of somewhat greater width than the width of a wall panel 11 supported thereon, so that the former may project a small distance beyond the plane of the surface of said wall panel as indicated at 13 in Fig. 8, thus forming in effect a bead or strip at an edge of the wall panel which will act as a fender or guard against objects being knocked against the sur-

face of the wall panel, marking or chipping the same. The projecting edge 13 may also be painted or plated with a color in contrast to the color of the wall panel and thereby increase 5 the external beauty and effect of the same.

The adaptation of the present invention to structures of the general class of cabinets is further illustrated in Figs. 9 and 10 of the drawings, and in keeping abreast with the modern trend 10 of cabinet design wherein the majority of the corners of such structures are rounded off by molding or other cabinet workers' methods, the curved corners of the frame as will be noticed, lend themselves admirably to this particular feature. It is important to note that the bottom 15 edge of the loop of metal displaced with respect to the adjacent portions of the leg 2 is relatively spaced with respect to the upper surface of the projecting leg 1 by reason of the formation of 20 the openings 3 in the angle bar so that a portion of metal is removed from both of the legs 1 and 2 respectively as previously described in detail. And this space intermediate the displaced metal and the upper surface of the horizontal 25 leg 1 is sufficient so that the peripheral flange 12 at the bottom of the stamped metal wall panel 11 may easily fit therebetween and beneath the displaced loop of metal to provide a further support and increase the strength of the wall 30 structure.

While the particular construction of the base frame has been specifically set forth for the purpose of description together with examples of its adaptation to several specific arrangements of 35 wall panel sections therewith, it is not intended that the invention be limited precisely thereto but that the same may have innumerable uses and adaptations so long as the same are within the scope of the annexed claims.

40 What I claim is:

1. A skeleton frame structure composed of bent angle bar stock and including alternately disposed corner and adjacent side portions each

having a substantially vertical leg and an integral horizontal leg projecting outwardly from one edge of said vertical leg, said vertical leg being severed from the horizontal leg at said corner portions and displaced to compensate for elongation in 5 said horizontal leg at the corner portions.

2. A skeleton frame composed of bent angle bar stock and including corner and adjacent side portions each having a vertical leg and an integral outwardly projecting horizontal base leg 10 the peripheral edge of which at said corner portions forms a circular arc having a radius substantially equal to the width of said leg in a side portion, said vertical leg being severed from the horizontal leg at the corner portions of the frame 15 and displaced to compensate for the elongation in said horizontal leg in arranging the same so that its peripheral edge forms a circular arc the radius of which is substantially equal to the width of said leg at a side portion. 20

3. A skeleton frame structure composed of bent angle bar stock and including alternately disposed corner and adjacent side portions each having a substantially vertical leg and a continuous horizontal leg projecting outwardly from said vertical 25 leg, said frame being constructed and arranged at said corner portions thereof so that the vertical leg is displaced laterally of the frame to compensate for elongation in said horizontal leg at the corner portions. 30

4. A skeleton frame composed of bent angle bar stock and including corner and adjacent side portions each having a vertical leg and a continuous outwardly projecting horizontal base leg, said frame being constructed and arranged at 35 said corner portions so that the vertical leg is displaced laterally of the frame to compensate for elongation in said horizontal leg in arranging the same so that its peripheral edge forms a circular arc the radius of which is substantially equal to 40 the width of said leg at a side portion.

WILLIAM D. ANTRIM.
